RAIL FASTENING MEANS FOR RAILWAY TIES

Filed Jan. 13, 1927

2 Sheets-Sheet 2

Patented June 28, 1927.

UNITED STATES PATENT OFFICE.

CHARLES W. LEE, OF LOCK HAVEN, PENNSYLVANIA.

RAIL-FASTENING MEANS FOR RAILWAY TIES.

Application filed January 13, 1927. Serial No. 160,879.

The invention relates to an improved means for fastening the rails of a railway to the ties, and has for its principal object the provision of a tie provided with a clamping means located beneath the rail plate and providing means to simultaneously engage the clamping means to hold the rail on the tie.

A further object of the invention is the provision of clamping means for railway rails associated with a railway tie, said clamping means being arranged in pairs under the bases of the rails seated on the tie and providing means actuated by a shaft located midway of the rails to engage the clamping devices to prevent movement of the rails relatively to the tie, the means engaging the clamping devices being simultaneously actuated to holding and releasing position.

20 The invention will be described in detail hereinafter and will be found illustrated in the accompanying drawings, in which

Figure 1 is a top plan view of a railway tie with improved fastening means mounted therein and showing fragments of railway rails secured thereto,

Figure 2 is a bottom plan view of the tie partly broken away,

Figure 3 is a side view in elevation,

30 Figure 4 is a fragmentary longitudinal sectional view on a plane indicated by the line 4-4 of Figure 1,

Figure 5 is a transverse sectional view on a plane indicated by the line 5-5 of Figure 1,

35 Figure 6 is a transverse sectional view on a plane indicated by the line 6-6 of Figure 1, and

Figure 7 is a detail perspective view of 40 one of the clamping members.

In the drawings similar reference characters will be used to designate corresponding parts in all of the views.

The improved fastening means to be hereinafter described is shown applied to a conventional railway tie that may be made of any suitable material designated 1. Rest plates 2 for the rails, designated A, are mounted on the tie adjacent to its two ends and are each provided with a recess 3 to receive the base of the rail A, the shoulders 4 defining the sides of the recess 3 by engaging the edges of the rest plate of the rail A to hold the rails from lateral displacement.

55 The ties 1 and rest plates 2 are provided with alined openings 5 in which are located tubu-

lar members 6. Clamping means for the rail A are mounted in the tubular members 6 and are arranged in pairs, as shown for each rail, said clamping members comprising semi-cylindrical stems 7 that snugly engage the bore of the tubular member in each instance, and having alined slots 8 therein for the purpose to be hereinafter stated. The upper ends of the stems 7 are 65 provided with laterally extending arms 9 that extend under the rail base, and have their outer ends returned to form hooks 10 to engage the side edges of the base of the rail. Rest plates 2 are provided with recesses 11 and the tubular members 6 have their upper ends notched as shown at 12 to receive the laterally extending arms 9.

Secured in a recess 13 in the bottom of the tie 1 is a housing 14 having a removable 75 cover plate 15. Slidably mounted in housing 14 are rods 16 that extend through openings 17 in the ends of the housing, and through alined openings 18 in the bottom of the tie. The outer ends of the rods 16 are adapted 80 to extend through slots 19 in tubular member 6 to engage the alined slots 8 in the stems 7 of the clamping members, the extremities of the rods being tapered as shown at 20 to insure engagement with the slots 8 and also that 85 the clamping members will be strained into clamping position. The adjacent ends of the rods 16 are offset in opposite directions as shown at 21 and have oppositely disposed parallel extensions 22 having their adjacent 90 edges provided with gear teeth 23. A shaft 24 is journaled in a tubular bearing at 25 arranged midway of the rest plates 2 and the lower end of the shaft 24 has a gear pinion 26 secured thereto and meshing with the 95 gear teeth 23. The upper end of the shaft 24 is provided with a polygonal extension 27 that may be engaged by a wrench or other suitable tool for rotating the shaft to actuate the rods 16 into and out of engaging position with the stems 7.

The operation of the device will be clearly understood from the drawings and the above description. It is clear that the two clamping members at each end of the tie 1 will be 105 locked in clamping position simultaneously by rotating the shaft 24 in one direction, and release of the rails may be readily effected when it is desired to remove them for renewal or other purpose by actuating the 110 shaft in the opposite direction, thus expediting the laying and removal of railroad

rails over the common practice of using spikes driven into the tie and furthermore that because of the structure of the fastening means the tie will not be mutilated by the means for fastening the railway rails thereto.

What is claimed is:—

1. Rail fastening means for railway ties, comprising a tie having a vertical opening, 10 clamping members slidably engaging in said opening and having alined longitudinal slots therein, said members provided with means to engage the base of a railway rail, a rod slidably engaging the tie and engaging in 15 said slots to hold the members in clamping positions, a shaft journaled in the tie, and

operative connections between the shaft and rod to move it into and out of engagement with the clamping members.

2. Rail fastening means for railway ties, 20 comprising a tie having a vertical opening, clamping members slidably engaging in said opening and having alined longitudinal slots 25 therein, said members provided with means to engage the base of a railway rail, a rod slidably engaging the tie and engaging in said slots to hold the members in clamping positions, a shaft journaled in the tie, a gear pinion on the shaft, and a rack carried by the rod and engaging the pinion.

In testimony whereof I affix my signature.

CHARLES W. LEE.
